UNITED STATES PATENT OFFICE.

HENRY BOSCH, OF CHICAGO, ILLINOIS, ASSIGNOR TO HENRY BOSCH COMPANY, OF CHICAGO, ILLINOIS, A CORPORATION OF ILLINOIS.

FEEDING MECHANISM.

1,208,084.

Specification of Letters Patent. Patented Dec. 12, 1916.

Application filed October 31, 1914. Serial No. 869,566.

To all whom it may concern:

Be it known that I, HENRY BOSCH, a citizen of the United States, residing at 525 Wabash avenue, Chicago, in the county of 5 Cook and State of Illinois, have invented a new and useful Improvement in Feeding Mechanism, of which the following is a specification.

My invention relates more particularly to 10 mechanisms for feeding superposed sheets of paper to cutting-mechanism for severing the sheets into strips of a predetermined length.

I have devised my improvement for use 15 more particularly in a machine of the general character above set forth, for use in the manufacture of wall paper sample-books. It is common practice in the manufacture of such sample-books to hang the various 20 rolls of paper from which the samples are to be made, on racks, with the free ends of the paper lying in superposed condition in a chute, with the various designs of the paper arranged in the order desired in the 25 finished sample-book, the superposed sheets extending into a position to be operated on by feed mechanism operating by an intermittent action to advance the superposed sheets by a similar movement, to mechanism 30 which cuts the sheets into sections of the desired length. The severed sheets are then stitched, or otherwise secured together, without disturbing the arrangement of the designs, and then trimmed.

35 Feed mechanisms suitable for the operation above stated, as hitherto constructed, have presented the primary objections of disarranging the ends of the sheets during the operation of clamping the sheets to the 40 feed device for advancing them to the cutting-mechanism and affording insufficient clearance of the clamping element in the return movement of the carriage; and furthermore, have been comparatively complicated and massive and readily susceptible to impairment.

My primary object is to provide a novel, simple, and comparatively inexpensive construction of feeding mechanism which will 45 not be liable to get out of order, may be readily adjusted for varying the amount of feed; and which will firmly grip the sheets without shifting one relative to the other

thereof, and thus preserve the desired relation of one sheet to the other, which is very 55 desirable, especially in the making of sample-books as it greatly reduces waste in trimming.

Referring to the accompanying drawings, Figure 1 is a view in side elevation of feeding mechanism constructed in accordance with my invention, the mechanism being shown as one of the elements in apparatus for the manufacture of wall paper sample-books, an end of the trough through which 65 the superposed sheets pass to the feed mechanism, and the adjacent end of the table of the cutting mechanism, being represented. Fig. 2 is a plan view section at the line 2 on Fig. 1 of the construction illustrated in 70 Fig. 1. Fig. 3 is a section taken at the line 3 on Fig. 2, and viewed in the direction of the arrow, these views showing the feed mechanism at the end of its stroke toward the paper supply to be drawn from, preliminary to its operation for clamping and advancing the sheets. Fig. 4 is a broken view 75 similar to Fig. 3, showing an intermediate position of the sheet-feeding means preparatory to the clamping of the paper. Fig. 5 is 80 a similar view showing the position of the parts of the feed mechanism after the sheet-clamping mechanism has moved to a position to clamp the sheets, and has been advanced throughout a portion of its path of 85 movement during the feeding of the sheets. Fig. 6 is a section taken at the line 6 on Fig. 1, and viewed in the direction of the arrow. Fig. 7 is a view in elevation, partly sectional, 90 of one of the similar adjusting devices for adjusting the movable one of said sheet-clamping members relative to its co-operating stationary member. Fig. 8 is an enlarged section taken at the line 8 on Fig. 3, and viewed in the direction of the arrow. 95 Fig. 9 is a section taken at the line 9 on Fig. 8, and viewed in the direction of the arrow. Fig. 10 is a section taken at the line 10 on Fig. 6, and viewed in the direction of the arrow; and Fig. 11, a section taken at the 100 line 11 on Fig. 10, and viewed in the direction of the arrow.

The supporting frame of my improved feed mechanism comprises end members 12 connected together by lower rods 13, a pair 105 of horizontally disposed rods 14, and struts

15, the tops of the end members 12 being connected together by parallel horizontally disposed bars 16 which form supports for the passage through the feed mechanism, of 5 the superposed sheets of paper to be fed and lying within the chute member hereinbefore referred to and represented at 17. The bars 14 form guides for a longitudinally reciprocable carriage 18 formed of a hollow 10 frame 19 having side members 20 formed with split sleeve-sections 21 at which the carriage engages the bars 14, a lower cross-bar 22, and an upper cross-bar 23, the latter of a length greater than the width of the 15 sheets of paper to be fed by the mechanism, the upper surface of the cross-bar 23 being grooved transversely, as indicated at 24, to receive the bars 16 which are preferably sprung upwardly as represented in Fig. 6 to 20 normally extend at their lower sides a slight distance above the bottoms of the grooves 24 and at their upper sides above the upper surface of the bar 23 for a purpose herein-after explained. 25 Fixed on the ends of the cross-bar 23 and rising from the latter are upright bars 25 containing slots 26 opening through the upper ends of these bars, the plane of these slots being at substantially right-angles to 30 the bar 23. Confined in the slots 26 to be vertically movable therein, is a presser-head 27 in the form of a plate extending at its ends into the slots 26, with the intermediate portion of its lower edge widened, as indicated at 28. The head 27 at its upper end carries spaced bearings 29 in which a shaft 30 having collars 31 fixed thereon by set-screws 32, is journaled. The ends of the shaft 30 are connected with the upper ends 40 of rods 33 which are pivotally connected as indicated at 34, with cranks 35 fixed on the ends of a shaft 36 journaled in bearings 37 provided on the side-bars 25 of the frame 18, whereby the presser-head 27 is 45 raised or lowered when the shaft 36 is rocked depending on the direction of its movement. The upper ends of the rods 33, which are screw-threaded, as represented at 38, pass through openings 39 in the ends 50 of the shaft 30 and have screwed thereon disks 40 containing notches 41 in their peripheries, and provided with hand-wheels 42, the portions of the disks 40 intermediate their notched portions and the hand-wheels 55 being of reduced diameter, as represented at 43, to provide grooves 44 into which flanges 45 on plates 46 secured to the ends of the shaft 30 by screws 47, extend, these plates carrying set-screws 48 each adapted to be 60 adjusted to enter the one of the notches 41 which opposes it. It will be understood from the foregoing that by turning the hand-wheels, assuming the set-screws 48 to have been adjusted to withdraw their ends 65 from the notches 41, the presser-head 27

may be adjusted toward or away from the bar 23, and the set-screws 48 thereafter turned to enter the opposing notches 41, to prevent disarrangement of the adjustment.

In the operation of the machine, the carriage 18 is reciprocated and the shaft 36 automatically actuated to draw the presser-head 27 downwardly into clamping engagement with the superposed strips of paper extending over the bar 23 of the carriage 70 during the movement of the carriage to the right in Fig. 1 for feeding a predetermined length of the superposed sheets to the cutting mechanism; and to raise the head out of the clamping engagement with the paper 75 before the carriage begins its return movement, viz., to the left in Fig. 1; these operations being effected by the following described mechanism: Fixed on the shaft 49 journaled in bearings 50 on the frame, is a 80 sprocket-wheel 51, the shaft 49 being adapted to be driven from a pinion 52 fixed on a collar 53 adapted to be releasably connected, by means of a clutch 54, with a drive-shaft 55, driven in any suitable manner, and 85 engaging a gear 56 fixed on the shaft 49. Located between the end-members 12 and in line with the sprocket 51 is a sprocket 57 journaled on a pin 58 having an enlarged inner end 59 flattened at its upper and 90 lower sides, as represented at 60 and 61 (Fig. 9), and fitting at said flattened portions between parallel bars 62 spaced apart and supported at their ends on the end-members 12. The pin 58 is adjustable toward and away from the sprocket 51 by 95 moving it along the guide-bars 62, and as a convenient means of providing for such adjustment I journal in one of the end-members 12 one end of a rod 63, which 100 parallels the bars 62 and screws at its threaded, opposite end 63^a into the pin 58, whereby upon turning the rod 63 the pin 58 is adjusted toward or away from the sprocket 51 depending on the direction in 105 which the rod 63 is turned. A sprocket-chain 64 engages the sprockets 51 and 57, and one of its links carries a pin 65 which extends laterally of the chain and pivotally connects with a pair of parallel links 66 110 spaced apart at the ends which engage the pin 65, by a washer 67, and straddling at their other ends one of the arms 68 of a rock-lever 69 rigidly connected at its upper end to the shaft 36, a pin 70 passing through 115 the arms 68 and links 66 and pivotally connecting these links with the lever 69 intermediate the ends of the latter. The lower end of the lever 69 carries a roller 71 located between the arms and confined therein by 120 a journal-pin 72 passing through these arms and the roller. The roller co-operates with a block 73 having its forward end rounded, as indicated at 73^a, this block being located beneath the roller and having threaded en- 125 130

gagement at a depending extension 74 thereon, with the screw-threaded portion 75 of a rod 76 journaled in the end-frames 12 and having an operating hand-wheel 77 for 5 turning the rod 76 to adjust the block 73 lengthwise of the machine, a rod 78 secured in the end-frames 12 to extend lengthwise of the machine, passing through the extension 74 and partially extending into a 10 groove in the bottom of the block 73, serving as a guide for the latter and holding it against turning.

The operation of the machine is as follows: Assuming the superposed strips of 15 paper to be operated on by the machine and illustrated at 80, to extend at their forward ends between the cross-bar 23 and the bar 27, and the carriage 18 to be at the limit of its return stroke, which is the position illustrated in Fig. 3, and in which position the head 27 is raised and the rock lever 69 inclines to the left in Fig. 3 with the roller above the block 73, rotation of the shaft 49 causes the chain 64 to travel in the direction 20 indicated by the arrow in Fig. 3, and by reason of the link-connection with the lever 69 moves the carriage 18 along the guides 14 to the right in this figure, the roller 71 bearing against the top of the block 73. The 25 carriage continues to move to the right in Fig. 3, as stated, until the roller reaches the forward end of the block 73, at which time the rock-member swings to the right in this figure under the action of the links 66 pulling 30 thereon with the result of rocking the shaft 36 in a direction to move the presser-head 27 downward into clamping engagement with the paper 80. As soon as the head has lowered sufficiently far to securely 35 clamp the paper between it and the bar 23 for overcoming the resistance offered by the paper to its movement along the machine (Fig. 5), in which operation the bars 16 yield downwardly, the carriage again moves 40 to the right in Fig. 3 drawing the paper 80 with it and advancing it to the cutting-mechanism above referred to, the carriage continuing to feed the paper, as stated, until the pin 65 passes over a horizontal line 45 drawn through the axis of the wheel 51, and starts to move to the left in Fig. 1. In this movement of the pin 65 the links 66 are shifted to the left in said figure, thereby 50 rocking the member 69 also to the left in this figure to the angular position represented in Fig. 3, which causes the presser-head 27 to be lifted out of engagement with the paper 80 before the carriage 18 starts on its return movement to the position illustrated in Fig. 3. The member 69 continues 55 to swing to the left in Fig. 3 until arrested in the angular position represented in this figure, by the engagement of the inner ends of the pins 34 with the underside of the cross-bar 23 (Fig. 6). As soon as the member 60

rocks to the position just stated the carriage starts to return to the position illustrated in Fig. 3, the paper being held out of engagement with the bar 23 by resting on the bars 16 which spring up as shown in Fig. 6 when 70 the head 27 rises, the carriage continuing this movement until the pin 65 passes above a horizontal line drawn through the axis of the sprocket 57, whereupon the carriage again moves to the right in Fig. 3 until the 75 roller passes the forward end of the block 73 at which time the presser-head 27 clamps the paper, and the feed of the carriage with the paper clamped thereto continues as hereinbefore explained. Thus the mechanism 80 operates automatically to feed the paper to the cutting-mechanism during the movement of the carriage in one direction only, thereby effecting intermittent feeding of the paper.

It will be readily understood from the 85 foregoing that by adjusting the block 73 lengthwise of the machine, the presser-head 27 may be caused to descend and clamp the paper at different stages in the movement of the carriage 18 to the right in Fig. 3, and thus the length of paper fed to the cutting-mechanism may be varied as desired. Furthermore, by this adjustment differences 90 in the thickness of the mass of sheets operated on, and the varying resistances afforded by the rolls of paper as they lessen in size, and from which the sheets 80 are drawn, may be compensated for, to insure the desired length of feed.

It is desirable that the carriage be held 100 against movement during the clamping and unclamping operations described, and as a desirable means for this purpose, I provide those illustrated which comprise split-rings 81 of leather, fiber, or other suitable material, which surrounds the shafts 14 and are confined in grooves 82 in split-collars 83 secured to the sleeves 21 as by bolts 84, clamp-screws 85 serving to hold the rings 81 against 105 the shafts 14 with the desirable pressure.

It will be apparent from the foregoing 110 that not only is a machine constructed in accordance with my invention, simple and positive in operation and readily adjustable for the purpose stated, but that by mounting the presser-head 27 to operate in a path at right angles to the sheets, there is no tendency to the shifting of the sheets relative to each other, and thus all of the sheets in a section of the stack of sheets severed by the cutting-mechanism will be of the same length, thereby reducing to the minimum the amount of waste in trimming. Furthermore, sufficient clearance is provided between the clamping-head 27 and the sheets to prevent contact of the head therewith on the return movement of the carriage.

While I have illustrated and described a particular embodiment of my invention, I do not wish to be understood as intending 130

to limit it thereto, as the same may be variously modified and altered without departing from the spirit of my invention.

What I claim as new and desire to secure by Letters Patent is:

1. In sheet-feeding mechanism, the combination of a reciprocable carriage, guide means on said carriage extending at right angles to the plane of movement of said carriage, a clamping member on said carriage and engaging said guide-means and movable up and down thereon and in parallelism with said carriage and in a path at a right angle to the path of movement of the carriage, for clamping sheets between it and said carriage, a rock-member connected with said carriage, means operated by said rock-member for actuating said clamping member, and means connected with said rock-member for rocking it to move said clamping member to clamping position and actuating the carriage, operating during a portion of their movement to move said clamping member into clamping engagement with the sheet without moving said carriage and thereafter, by the clamping action produced, move said carriage and with it the sheet.
2. In sheet-feeding mechanism, the combination of a reciprocable carriage, a clamping member on said carriage and movable up and down thereon, and in parallelism therewith, and in a path at a right angle to the path of movement of the carriage, for clamping sheets between it and said carriage, a rock-member connected with said carriage, means operated by said rock-member for actuating said clamping member, and means connected with said rock-member for rocking it to move said clamping member to clamping position and actuating the carriage, operating during a portion of their movement to move said clamping member into clamping engagement with the sheet without moving said carriage and thereafter, by the clamping action produced, move said carriage and with it the sheet, said last-named means being adjustable for varying the length of feed.
3. In sheet-feeding mechanism, the combination of a reciprocable carriage, a clamping member on said carriage movable relative to said carriage and adapted to clamp sheets between it and said carriage, a rock-member connected with the carriage, means operated by said rock-member for actuating said clamping member, means connected with said rock-member for rocking it to move said clamping member to clamping position and operating thereafter to advance said carriage, and means for preventing rocking of said rock-member under the action of said second-named means, until said carriage has moved a predetermined distance.
4. In sheet-feeding mechanism, the com-

bination of a reciprocable carriage, a clamping member on said carriage movable relative to said carriage and adapted to clamp sheets between it and said carriage, a rock-member connected with the carriage, means operated by said rock-member for actuating said clamping member, means connected with said rock-member for rocking it to move said clamping member to clamping position and operating thereafter to advance said carriage, and adjustable means for preventing rocking of said rock-member under the action of said second-named means until said carriage has moved a predetermined distance.

5. In sheet-feeding mechanism, the combination of a reciprocable carriage, a movable clamping member on said carriage for clamping sheets between it and said carriage only by pressure exerted by said clamp, a rock-member on said carriage, means connected with said rock-member and with said clamping member for actuating the latter, a traveling member, and a member connecting said traveling member with said rock-member, for the purpose set forth.

6. In sheet-feeding mechanism, the combination of a reciprocable carriage, a clamping member on said carriage for clamping sheets between it and said carriage, a rock-member on said carriage, means connected with said rock-member for actuating said clamping member, a traveling member, a member connecting said traveling member with said rock-member, and means for preventing rocking of said rock-member under the action of said traveling member, until said carriage has moved a predetermined distance.

7. In sheet-feeding mechanism, the combination of a reciprocable carriage, a clamping member on said carriage for clamping sheets between it and said carriage, a rock-member on said carriage, means connected with said rock-member for actuating said clamping member, a traveling member, a member connecting said traveling member with said rock-member, and means for preventing rocking of said rock-member under the action of said traveling member, until said carriage has moved a predetermined distance, adjustable for regulating the length of feed.

8. In sheet-feeding mechanism, the combination of a reciprocable carriage, a clamping member on said carriage movable up and down thereon in a path at a right-angle to the path of movement of the carriage and adapted to clamp sheets between it and said carriage, a rock-member on the carriage, means operated by said rock-member for actuating said clamping member, means connected with said rock-member for rocking it to move said clamping member to clamping position and operating thereafter to ad-

vance said carriage, and means for preventing rocking of said rock-member under the action of said second-named means, until said carriage has moved a predetermined distance.

5 9. In sheet-feeding mechanism, the combination of a reciprocable carriage, a clamping member on said carriage movable up and down thereon in a path at a right-angle to the path of movement of the carriage and adapted to clamp sheets between it and said carriage, a rock-member connected with the carriage, means operated by said rock-member for actuating said clamping member, means connected with said rock-member for rocking it to move said clamping member to clamping position and operating thereafter to advance said carriage, and adjustable means for preventing rocking of said rock-member under the action of said second-named means, until said carriage has moved a predetermined distance.

10 10. In sheet-feeding mechanism, the combination of a reciprocable carriage, a clamping member on said carriage, movable up and down thereon in a path at a right-angle to the path of movement of the carriage for clamping sheets between it and said carriage, a rock-member on said carriage, means connected with said rock-member for actuating said clamping member in a direction relative to said carriage, a traveling member, and a member connecting said traveling member with said rock-member for actuating said clamping member relative to said carriage and moving said carriage, for the purpose set forth.

15 11. In sheet-feeding mechanism, the combination of a reciprocable carriage, a clamping member on said carriage movable up and down thereon in a path at a right-angle to the path of movement of the carriage for clamping sheets between it and said carriage, a rock-member on said carriage, means connected with said rock-member for actuating said clamping member, a traveling member, a member connecting said traveling member with said rock-member, and means for preventing rocking of said rock-member under the action of said traveling member, until said carriage has moved a predetermined distance.

20 12. In sheet-feeding mechanism, the combination of a reciprocable carriage, a clamping member on said carriage movable up and down thereon in a path at a right-angle to the path of movement of the carriage for clamping sheets between it and said carriage, a rock-member on said carriage, means connected with said rock-member for actuating said clamping member, a traveling member, a member connecting said traveling member with said rock-member, and means for preventing rocking of said rock-member under the action of said traveling member,

until said carriage has moved a predetermined distance, adjustable for regulating the length of feed.

25 13. In sheet-feeding mechanism, the combination of a reciprocable carriage, a clamping member on said carriage and adapted to clamp sheets between it and said carriage, a rock-member on said carriage, means connected with said rock-member for actuating said clamping member, a member adapted to be moved in an endless path, and a member connecting said last-named member with said rock-member, for the purpose set forth.

30 14. In sheet-feeding mechanism, the combination of a reciprocable carriage, a clamping member on said carriage and adapted to clamp sheets between it and said carriage, a rock-member on said carriage, means connected with said rock-member for actuating said clamping member, a member adapted to be moved in an endless path, a member connecting said last-named member with said rock-member, and means for preventing rocking of said rock-member under the action of said traveling member, until said carriage has moved a predetermined distance.

35 15. In sheet-feeding mechanism, the combination of a reciprocable carriage, a clamping member on said carriage and adapted to clamp sheets between it and said carriage, a rock-member on said carriage, means connected with said rock-member for actuating said clamping member, a member adapted to be moved in an endless path, a member connecting said last-named member with said rock-member, and means for preventing rocking of said rock-member under the action of said traveling member until said carriage has moved a predetermined distance.

40 16. In sheet-feeding mechanism, the combination of a reciprocable carriage, a clamping member on said carriage movable up and down thereon in a path at a right-angle to the path of movement of the carriage for clamping sheets between it and said carriage, a rock-member on said carriage, means connected with said rock-member for actuating said clamping member, a member adapted to be moved in an endless path, and a member connecting said last-named member with said rock-member, for the purpose set forth.

45 17. In sheet-feeding mechanism, the combination of a reciprocable carriage, a clamping member on said carriage movable up and down thereon in a path at a right-angle to the path of movement of the carriage for clamping sheets between it and said carriage, a rock-member on said carriage, means connected with said rock-member for actuating said clamping member, a member adapted to be moved in an endless path, a member connecting said last-named member

with said rock-member, and means for preventing rocking of said rock-member under the action of said traveling member, until said carriage has moved a predetermined distance.

18. In sheet-feeding mechanism, the combination of a reciprocable carriage, a clamping member on said carriage movable up and down thereon in a path at a right-angle to the path of movement of the carriage for clamping sheets between it and said carriage, a rock-member on said carriage, means connected with said rock-member for actuating said clamping member, a member adapted to be moved in an endless path, a member connecting said last-named member with said rock-member, and means for preventing rocking of said rock-member under the action of said traveling member, until said carriage has moved a predetermined distance, adjustable for regulating the length of feed.

19. In sheet-feeding mechanism, the combination of a reciprocable carriage, a clamping member on said carriage movable relative to said carriage and adapted to clamp sheets between it and said carriage, a rock-member on said carriage, means connected with said rock-member for actuating said clamping member, a suitably supported endless sprocket-chain, means for driving said chain, and a link connected with said chain and with said rock-member.

20. In sheet-feeding mechanism, the combination of a reciprocable carriage, a clamping member on said carriage movable up and down thereon in a path at a right-angle to the path of movement of the carriage for clamping sheets between it and said carriage, a rock-member on said carriage, means connected with said rock-member for actuating said clamping member, a member adapted to be moved in an endless path, a member connecting said last-named member with said rock-member, and means for preventing rocking of said rock-member under the action of said traveling member, until said carriage has moved a predetermined distance.

21. In sheet-feeding mechanism, the combination of a reciprocable carriage, a clamping member on said carriage movable relative to said carriage and adapted to clamp sheets between it and said carriage, a rock-member on said carriage, means connected with said rock-member for actuating said clamping member, a suitably-supported endless sprocket-chain, means for driving said chain, a link connected with said chain and with said rock-member, and means for preventing rocking of said rock-member under the action of said link, until the carriage has moved a predetermined distance, adjustable for regulating the length of feed.

22. In sheet-feeding mechanism, the com-

bination of a reciprocable carriage, a clamping member on said carriage movable up and down thereon in a path at a right-angle to the path of movement of the carriage for clamping sheets between it and said carriage, a rock-member on said carriage, means connected with said rock-member for actuating said clamping member, a suitably supported endless sprocket-chain, means for driving said chain, and a link connected with said chain and with said rock-member.

23. In a sheet-feeding mechanism, the combination of a reciprocable carriage, a clamping member on said carriage movable up and down thereon in a path at a right-angle to the path of movement of the carriage for clamping sheets between it and said carriage, a rock-member on said carriage, means connected with said rock-member for actuating said clamping member, a suitably supported endless sprocket-chain, means for driving said chain, a link connected with said chain and with said rock-member, and means for preventing rocking of said rock-member under the action of said link, until said carriage has moved a predetermined distance, adjustable for regulating the length of feed.

24. In sheet-feeding mechanism, the combination of a reciprocable carriage, a clamping member on said carriage movable up and down thereon in a path at a right-angle to the path of movement of the carriage, a rock-shaft on said carriage, means connected with said rock-shaft and with said clamping member for actuating the latter, a lever connected with said rock-shaft, an endless traveling member, a link connected with said endless member and with said lever, and a block adapted to be engaged by said lever during a portion of the movement of said traveling member and operating to prevent the movement of said clamping member to clamping position until said lever passes said block.

25. In sheet-feeding mechanism, the combination of a reciprocable carriage, a clamping member on said carriage movable up and down thereon in a path at a right-angle to the path of movement of the carriage, a rock-shaft on said carriage, means connected with said rock-shaft and with said clamping member for actuating the latter, a lever connected with said rock-shaft, an endless traveling member, a link connected with said endless member and with said lever, and a block supported on the machine to be adjustable lengthwise of the path of movement of said carriage, said block being adapted to be engaged by said lever during a portion of the movement of said traveling member and operating to prevent the movement of said clamping member to clamping position until said lever passes said block.

26. In sheet-feeding mechanism, the com-

5 bination of a reciprocable carriage, a clamping member on said carriage and movable up and down thereon in a path at a right-angle to the path of movement of said carriage, a rock-shaft journaled on the carriage and having crank connection with said clamping member, a lever connected with said rock-shaft, sprocket-wheel supported on the machine, a sprocket-chain engaging 10 said wheels, means for actuating said wheels, a link connected at one end with said chain and at its opposite end with said lever intermediate the ends of the latter, and a block mounted to be adjustable lengthwise 15 of the machine and adapted to be engaged by the lower end of said lever and operating to prevent said rock-shaft from moving to a position in which said clamping member clamps the sheets, until said carriage 20 has moved a predetermined distance.

27. In sheet-feeding mechanism, the combination of a reciprocable carriage, a clamping member on said carriage movable relative thereto and adapted to clamp sheets 25 between it and said carriage, a rock-member connected with said carriage, means actuated by said rock-member for actuating said clamping-member, and means connected with said rock-member operating to exert 30 force in the plane of movement of said carriage, said rock-member being pivoted to said carriage in a plane crosswise of the plane in which said means operate, whereby said last-named means operate to move said 35 clamping-member to clamping position and thereafter advance said carriage.

28. In sheet-feeding mechanism, the combination of a reciprocable carriage, a clamping member on said carriage movable relative thereto and adapted to clamp sheets 40 between it and said carriage, a rock-member connected with said carriage, means operated by said rock-member for actuating said clamping member, an arm connecting 45 said rock-member, and means connected with said arm operating to exert force in the plane of movement of said carriage, said rock-member being pivoted to said carriage in a plane crosswise of the 50 plane in which said means operate, whereby said last-named means operate to move said clamping member to clamping position and thereafter advance said carriage.

29. In sheet-feeding mechanism, the combination of a reciprocable carriage, a clamping member on said carriage movable relative thereto and adapted to clamp sheets 55 between it and said member, a rock-member connected with said carriage, an arm on 60 said rock-member, a surface against which said arm moves restraining the rocking of said rock-member to a position in which said clamping member is in clamping position, and means operatively connected with 65 said rock-member for rocking the latter, ex-

cepting as restrained by said surface, and shifting said carriage.

30. In sheet-feeding mechanism, the combination of a reciprocable carriage, a clamping member on said carriage movable relative thereto and adapted to clamp sheets 70 between it and said member, a rock-member connected with said carriage, an arm on said rock-member, a surface against which said arm moves restraining the rocking of 75 said rock-member to a position in which said clamping member is in clamping position, and means operatively connected with said rock-member for rocking the latter, excepting as restrained by said surface, and 80 shifting said carriage, said surface being adjustable lengthwise of said carriage to vary the point at which the clamping operation takes place.

31. In sheet-feeding mechanism, the combination of a reciprocable carriage, a clamping member on said carriage movable relative thereto and adapted to clamp sheets 85 between it and said member, a rock-member connected with said carriage, an arm on 90 said rock-member, a surface against which said arm moves restraining the rocking of said rock-member to a position in which said clamping member is in clamping position, and means operatively connected with said 95 rock-member for rocking said rock-member, excepting as restrained by said surface, and moving said carriage.

32. In sheet-feeding mechanism, the combination of a reciprocable carriage, a clamping member on said carriage movable relative thereto and adapted to clamp sheets 100 between it and said carriage, a rock-member connected with said carriage, means connecting 105 said rock-member with said clamping member and operating to move the latter relative to the carriage, an arm on said rock-member, a drive member, and a connector between said drive member and said arm, said arm extending at an angle to the direction of force exerted against it by said connector.

33. In sheet-feeding mechanism, the combination of a reciprocable carriage, a clamping member on said carriage movable relative thereto and adapted to clamp sheets 115 between it and said carriage, a rock-member connected with said carriage, means connecting 120 said rock-member with said clamping member and operating to move the latter relative to the carriage, an arm on said rock-member, a drive member, and a link pivotally connected with said arm and with said drive member, said arm extending at an angle to the direction of force exerted 125 against it by said link.

34. In sheet-feeding mechanism, the combination of a reciprocable carriage, a clamping member on said carriage and movable toward and away from the latter, and means 130

for causing the clamping member to clamp the sheet for feeding it, at one of a number of points at the beginning of the movement of said carriage, in a direction for feeding, without varying the feed at the other end of the movement of said carriage.

35. In sheet-feeding mechanism, the combination of a reciprocable carriage, guide-means on said carriage extending at a right angle to the plane of movement of said carriage, a clamping member engaging and movable along said guide-means toward and away from said carriage, and means connected with said clamping member for actuating the latter and operating by the clamping grip of the clamp on the paper to advance the carriage in the sheet-advancing operation.

36. In sheet-feeding mechanism, the com-

bination of a reciprocable carriage, guide-means on said carriage extending at a right angle to the plane of movement of said carriage, a clamping member engaging and movable along said guide-means toward and away from said carriage, and means connected with said clamping member by which the latter is moved toward said carriage and the carriage is actuated, operating to move said clamping member into engagement with the sheet, without moving said carriage, and thereafter, by the clamping action produced, move said carriage and with it the sheet.

HENRY BOSCH.

In presence of—

L. HEISLAR,
N. B. DEARBORN.
